SPRING ACTUATED TOY

Albert Stubbmann, Franklin Lakes, N.J., assignor to
General Foods Corporation, White Plains, N.Y.

Filed Aug. 11, 1971, Ser. No. 171,046

Term of patent 14 years

Int. Cl. D21—01

U.S. Cl. D34—15 M

FIG. 1

FIG. 2

FIG. 3

FIG. 4

FIG. 5

FIG. 6

FIG. 1 is a perspective view of a spring actuated toy in accordance with my invention showing projectible marbles at rest on their respective platforms;

FIG. 2 is a front elevational view thereof;

FIG. 3 is a right-hand side elevational view thereof;

FIG. 4 is a rear elevational view thereof;

FIG. 5 is a top plan view thereof; and

FIG. 6 is a bottom plan view thereof.

I claim:

The ornamental design for a spring actuated toy, as shown and described.
